W. H. ELLIOT.
ROCK EXCAVATOR.

No. 65,801.

Patented June 18, 1867.

United States Patent Office.

WILLIAM H. ELLIOT, OF NEW YORK, N. Y.

Letters Patent No. 65,801, dated June 18, 1867.

IMPROVED ROCK-EXCAVATOR.

The Schedule referred to in these Letters Patent and making part of the same.

TO ALL WHOM IT MAY CONCERN:

Be it known that I, Wm. H. ELLIOT, of the city, county, and State of New York, have invented new and improved Machinery for Excavating Rock and Ore; and I do hereby declare that the following is a full and exact description thereof, reference being had to the accompanying drawings, and to the letters of reference marked thereon.

Similar letters of reference indicate the same devices in all the figures.

To enable others skilled in the arts to comprehend, make, and use my invention, I will proceed to describe its nature, construction, and operation.

The nature of my invention consists in suspending from a car, which is provided with wheels which run upon tracks or ways near or above the surface of the earth, a drilling machine for drilling rocks, ores, and such like substances, and also in suspending a platform for the support of a drilling machine, pulleys, belts, &c., the whole being suspended by iron rods, wire, ropes, or other adjustable supports, the power for driving the drilling machine being derived from a steam engine on the car, which is so employed as to drive the car along upon the track, or to drive the machinery suspended under it; in providing proper braces for the platform and machinery, to hold them in a fixed position while the machinery is running; in providing suitable stops for the car, to prevent it from moving; and in conveying the power of the engine from the car to the platform, or the drilling machines thereon, by means of belts and pulleys, conducting pipes, or other suitable devices.

Figure 1 is a cross-section of a street sewer, showing the car, steam engine, suspended platform, and drilling machine.

Figure 2 is a longitudinal vertical section of the same, with a section of the car and an elevation of the machinery.

Figure 3 is a cross vertical section of a deep mine, showing several drilling machines suspended from a car.

Figure 5 shows the application of the same invention to the excavation of canals, cellars, &c.

a, car, upon which stands *b*, the steam engine. *c*, the platform, suspended by means of rods, *f*, or wire ropes, *f'*, from the car. *d*, sub-car, for the support of car *a* over broad cuts. *e*, drilling machines supported by the platform. *g*, windlass for raising or lowering the platform when wire ropes are employed for supports. *g'*, screw-nuts for the same purpose when rods are employed. *h*, car-wheels. *h'*, tracks or ways upon which the wheels run. *i* and *i'*, wheels and track which support the sub-car *d*. *k*, belt connecting the fly-wheel of the engine with pulley *l*. *l*', belt connecting pulley *l* with pulley *l''*, shown in dotted lines, on the same shaft with pulley *m*. *m'*, fly-wheel of the drilling machine, connected with pulley *m* by a round belt. A round belt is employed here, so that the varying positions of the drilling machine shall not derange it. Pulleys *m* and *l''* are supported on the top of swinging frame *m''*, which has its hinge around shaft *x*, and is caused, by a spring or weight, to swing from the drilling machine, so as to keep its belt always tight and accommodate its movements. *n*, crank of the drilling machine. *n'*, connecting-rods. *o*, braces on the platform, which rest against the rock. *o'*, brace between the car and the platform. *p*, stop, which is fastened at its lower end to the track, and hinged at its upper end to the car, for holding the car stationary. *q*, gear on one of the axles of the car. *q'*, pinion meshing into gear *q*. *r*, tight and loose pulleys on the same shaft with pinion *q'*. *r'*, belt connecting pulleys *r* with the engine. *r'*, drill attached to the drilling machine.

Steam engines and rock-drilling machines are so well known that it is not necessary for the purposes of this application that they should be shown or specified in detail. Almost any of the portable engines now in use may be employed for this purpose, and any practical rock-drill may be used, whether propelled by belts, compressed air, or by steam.

My invention refers to the handling, applying, and working of any rock-drill in deep rock cutting, mines, &c.

Figs. 1 and 2 show the application of my invention to sewers. These are usually cut from four to six feet wide, and from ten to eighteen feet deep. The two tracks *h'* are first laid down on the street at a proper distance from each other, and the earth removed between them where the sewer is to be made. The car, with its suspended machinery, is then run upon the track and passed over its entire length, drilling, as it comes to them, the higher points of the rock for blasting. The machine is then lowered two or three feet and passed over the length of the sewer again, drilling all the rock within its reach, and so on, lowering the bottom of the sewer two or three feet each time the machine passes over it. When it is necessary to move the car from one place

to another on the track, the stop p is detached from the track, the belt r' run on to the tight pulley, when the car will move slowly off. Having moved far enough to bring the drills to a proper point for other holes, the car is stopped, the stop p fastened to the track, the braces o run out against the sides of the cut, the machine lowered to the rock and started up. The platform for narrow sewers should have one machine upon it at each end; for wide sewers it should have two machines at each end. The swinging frame may be placed upon the car in a horizontal position, with pulley m over m' . This would accommodate the motions of the drilling machine, and allow the platform to be raised high enough to drill upon the surface. Following this car at a proper distance there should be another car, propelled by an engine carrying a steam crane, and a shield, composed of timber bolted together, so that when several holes have been charged the car may be caused to carry the shield over them to confine the flying fragments of rock when the explosion takes place. After blasting, the steam crane may be used to raise the detached rock.

Fig. 3 shows the application of my invention to deep vertical mines. The drilling machines at the bottom of the mine are driven from the fly-wheel of the engine by a system of belts and pulleys reaching from one platform to another from the top to the bottom of the mine. The director of the work would find it necessary to remain at the bottom of the mine, and to enable him to operate the engine for driving or moving the machinery, there should be a system of levers and connecting-rods reaching from the lower platform to the engine. To communicate his wishes to the fireman there should be a speaking-tube and a bell both at top and bottom, with the necessary bell wires. There should also be a stairway or hoisting apparatus, for the use of laborers. In addition to these appliances, there should be a force-pump for draining the mine and for producing a small powerful stream of water for washing chip out of drill holes. There should also be attached to the car a fan-blower for ventilating the mine, and a gas apparatus, with gas pipes descending to the bottom of the mine, for lighting it. The drilling machinery for mines, like that for sewers, should be made to travel the entire length of the mine, drilling rows of holes across the mine at proper distances, and moving along by the locomotive power of the engine, as occasion requires. Following this at a convenient distance, the blasting and elevating machinery would do its work, the whole travelling over the mine from one end to the other, reducing the bottom about three or four feet each time it passes along. The adjustable supports reaching from the lower platform to the first one above it should be of wire rope wound upon windlasses, so that the machines may be lowered conveniently as the mine deepens. It may be necessary in some cases to place the steam engine on the suspended platform, but in most cases it will need to be on the car.

Fig. 5 shows the application of my invention to the excavation of canals and cellars, and all rock-cutting of similar character. This differs from the other principally in the employment of a sub-car, d , which stretches across the excavation, carrying the car a , with its engine, suspended platform, and machinery. Sub-car d moves longitudinally over the excavation, while the car it supports moves across it, to bring the drills to any required point. The steam engine should be so connected with the sub-car as to cause it to move upon its tracks h' .

Having described my invention, what I desire to have secured to me by Letters Patent of the United States, is—

1. The combination of car a , tracks h' , and drilling machine e , when said machine is suspended from a car, substantially as herein shown and described.
2. Platform e , in combination with car a and drilling machine e , substantially as and for the purpose herein set forth.
3. Adjustable supports f and f' , in combination with car a and drilling machine e , substantially as and for the purpose herein shown.
4. Frame m'' , in combination with drilling machine e , and platform e , for the purpose herein set forth.
5. Braces o , in combination with platform e , substantially as and for the purpose herein set forth.

WM. H. ELLIOT.
